DESIGN FOR A PREFABRICATED BUILDING

H. F. Pettigrew and Winfield Morten, Dallas, Tex., assignors to Texas Prefabricated House & Tent Company, Dallas, Tex., a partnership composed of Winfield Morten and H. F. Pettigrew

Application November 10, 1941, Serial No. 104,104

Term of patent 14 years

To all whom it may concern:

Be it known that we, H. F. Pettigrew and Winfield Morten, citizens of the United States of America, residing at Dallas, in the county of Dallas and State of Texas, have invented a new, original, and ornamental Design for a Prefabricated Building, of which the following is a specification, reference being had to the accompanying drawing, forming part thereof.

Figure 1 is a perspective view of a prefabricated building, showing our new design,

Figure 2 is a front elevation of the building,

Figure 3 is a side elevation of the building, and Figure 4 is a top plan view of the building.

The characterizing features of our design reside in a building having the specific configuration, proportions, and arrangement of parts specifically as shown.

We claim:

The ornamental design for a prefabricated building as shown and described.

H. F. PETTIGREW.
WINFIELD MORTEN.
